H. G. PAPE,
MECHANICAL MOVEMENT,
APPLICATION FILED APR. 17, 1916.

1,216,483.

Patented Feb. 20, 1917.

UNITED STATES PATENT OFFICE.

HERMAN G. PAPE, OF NEW YORK, N. Y., ASSIGNOR TO RALPH A. SCHOENBERG, OF NEW YORK, N. Y.

MECHANICAL MOVEMENT.

1,216,483.

Specification of Letters Patent. Patented Feb. 20, 1917.

Application filed April 17, 1916. Serial No. 91,789.

To all whom it may concern:

Be it known that I, HERMAN G. PAPE, of New York city, in the county and State of New York, have invented a new and useful Mechanical Movement, of which the following is a specification.

The main object of my invention is to provide a mechanical movement of simple construction in which the driving member actuates the driven member with a quick snap movement.

One feature of my invention consists in a longitudinally moving driving member for accomplishing this object and in the preferred form I provide a rocking member and an actuator for the rocking member, said actuator being put in position for actuation by means of a spring.

Another feature consists in means movable 20 in the same direction to actuate the rocker in different directions.

Other features of my invention will be pointed out below.

In the drawings:

25 Figure 1 is an elevation of an electric switch embodying my invention;

Fig. 2 is an elevation partly in section at a right angle to the position of Fig. 1;

Fig. 3 is a plan of the switch of Fig. 2;

30 Fig. 4 is a fragmentary section of the bridging member on the line 4—4 of Fig. 3; and

Fig. 5 is a section on line 5—5 of Fig. 3, with certain portions of the switch omitted.

35 In the drawings I show my invention embodied in an electric switch.

Base portion A of insulating material is connected by screw a with center contact a', the latter being extended vertically to form 40 a moving conductor a². A similar moving conductor a³ is connected by screw a⁴ to the other side of base portion A.

Frame member B of insulating material is notched at b' and in notch b is conductor 45 B' in sliding engagement with conductor a³, the upper portion of conductor B' extending partly across the top of member B and held thereto by screw D. The conductor B' is slotted at b² to receive conductor a² and has 50 a pocket in which is mounted coiled spring b⁴ co-operating with plunger b⁵ and tending to press members A and B apart. Conductor B² is slotted at b⁶ to slidingly engage conductor a² and has a pocket for coiled spring b⁷ 55 which engages plunger b⁸ and tends to press

members A and B apart. Conductor B² is held to member B by screw b⁹ and carries binding screw b¹⁰.

Supporting yoke E and limiting yoke E' are held to member B by screw e. Rocker F 60 has a shaft f whose end bearings are in yoke E, the shaft f having an eccentric portion f' to which is connected one end of coiled spring f², the other end being connected by eye f³ to the bridging member G, which is 65 also pivoted on shaft f. The limiting yoke E' is engaged by the portion f' so that the latter can not oscillate beyond a certain limit in either direction.

Pivoted at g to member A is operating 70 lever G', slotted at g' and carrying pin g² which rides in the slot f⁴ of rocker F, the slot g' engaging one end of spring H which extends around screw h and across member G and into aperture h' so that the spring H 75 is anchored against turning, the screw h, when screwed in, aiding in holding the spring in place.

Member G bridges the two contacts K-K', 80 contact K and metal washer k being held in position by screw D. Contact K' is held in place by screw k' which also holds plate k² in position, plate k² carrying binding post k³.

The circuit is through binding post k³, 85 contact K', member G, contact K, screw D, members B' and a³, screw a⁴, shell a⁵, the lamp or other electrical appliance (not shown), center contact a', members a² and B² and binding post b¹⁰.

I preferably provide a tubular insulating 90 covering a⁶ of fiber or the like outside the screw shell a⁵ and my whole device may be housed in any suitable casing such as a shell and cap.

The screw shell a⁵ is a support for the lamp or other electrical appliance that may be used and with the members a² and a³ moves longitudinally with relation to members B, B' and B². Assuming the parts to be as shown, operation is had by pushing the support inward, or toward the switch mechanism proper, the first effect being that pin g² rides to the right in slot f⁴ and lifts the right end of rocker F carrying with it the end f⁵ of spring f² and when this end has passed the line extending from f³ through pivot f the spring which has been expanded will be free to contract and swing bridging member G on its pivot until its left end is 105 110

raised into engagement with contacts K and K', this movement being accomplished with a quick snap to make the circuit. The hand will now be released and springs b^4 and b^7 will press members A and B apart, the separation being limited by pin g^2 engaging the lowest part of slot f^4 . It is to be observed that if pin g^2 were at rest immediately beneath pivot f then it would be difficult to press the shell a^5 inwardly so I provide spring H to swing lever G' slightly to one side or the other of the dead center in order that pin g^2 may move freely in slot f^4 when the operation is started. In the position shown that end of the spring H which is attached by screw h to member G is, as compared with the other position of oscillation of member G, relatively removed from slot g' and therefore the tendency is to pull the free end of spring H toward the right with the consequence that pin g^2 rests slightly to the right of the dead center. When however, the left end of the bridging member G has been raised to make the circuit that end of spring H which is fixed to member G is brought relatively close to slot g' so that when the shell a^5 is moved outwardly spring H will tend to expand and therefore push lever G' slightly to the left of the dead center and pin g^2 will therefore be ready on the next operation to lift the left end of the rocker F which will lower the end f^6 of spring f^2 so as to break the circuit and this movement will return the parts to the position shown, spring H having acted to pull lever G' slightly to the right of the dead center.

What I claim is:

1. A mechanical movement comprising a pivoted driven member extending on both sides of its pivot; a driving member to engage said driven member alternately at opposite sides of the pivot of said driven member; and positive means separate from the driven member acting to move said driving member away from its central position to accomplish such alternate engagement.

2. A mechanical movement comprising a pivoted driven member; a pivoted driving member to engage directly said driven member, the pivot of said driving member being movable; and a spring to shift said driving member from its central position so that it will engage said driven member alternately at opposite sides of the pivot of said driven member.

3. A mechanical movement comprising a pivoted driven member; a pivoted driving member to engage said driven member alternately at opposite sides of the pivot of said driven member, the pivot of said driving member being movable; and a spring to swing said driving member on its pivot away from its central position.

4. A mechanical movement comprising a

pivoted driven member; a bodily movable driving member to engage said driven member alternately at opposite sides of the pivot of said driven member; and a spring actuated by the driven member to shift said driving member to accomplish such alternate engagement.

5. A mechanical movement comprising a pivoted driven member; a pivoted driving member to engage said driven member alternately at opposite sides of the pivot of said driven member, the pivot of said driving member being movable; and a spring actuated by the driven member to swing said driving member on its pivot.

6. A mechanical movement comprising a rocker; a lever mounted to move bodily toward and from said rocker and operating to shift said rocker alternately in opposite directions; and means moved by the rocker and moving to shift the lever from its central position to cause the lever to shift the rocker alternately in opposite directions.

7. A mechanical movement comprising a rocker; a lever mounted to move bodily toward and from said rocker and operating to shift said rocker alternately in opposite directions; and a spring actuated by the rocker and moving the lever from its central position to cause the lever to shift the rocker alternately in opposite directions.

8. A mechanical movement comprising a rocking member; a spring, one of whose ends is swung by the rocking member to put the spring under stress; a member shifted by the stress of said spring; and a driving member moving longitudinally in one direction to actuate the rocking member in opposite directions; and positive means separate from the rocking member acting to move said driving member away from its central position to accomplish said rocking in opposite directions.

9. A mechanical movement comprising a rocking driven member; a driving member shiftable to engage said driven member alternately at opposite sides of its pivot; a second rocking member actuated by the rocking of the driven member to rock in the direction opposite to that in which the driven member rocks; and means separate from the driven member and actuated by said second rocking member to shift the driving member to accomplish said alternate engagement with the driven member, said means including a portion movable with relation to the driven member.

10. A mechanical movement comprising a rocking driven member; a driving member shiftable sidewise to engage said driven member alternately at opposite sides of its pivot, said driving member being capable of bodily reciprocation, movement in one direction of its reciprocation rocking said driven member in one direction of its rock-

ing and also movement in the same direction of its reciprocation rocking said driven member in the opposite direction of its rocking; and a spring to shift said driving member away from its central position to accomplish said alternate engagement.

11. A mechanical movement comprising a pivoted driven member; a pivoted driving member to engage said driven member alternately at opposite sides of the pivot of said driven member, the pivots of the driven and driving members being parallel and the pivot of the driving member being movable; and a spring to swing said driving member 15 on its pivot away from its central position.

12. A mechanical movement comprising a rocking driven member; a driving member

shiftable to engage said driven member alternately at opposite sides of its pivot; a second rocking member actuated by the driven member; and means connecting the second rocking member and the driving member to shift the latter to accomplish said alternate engagement.

13. A mechanical movement comprising a rocking driven member; a driving member shiftable to engage said driven member alternately at opposite sides of its pivot; a second rocking member actuated by the driven member; and a spring connecting the second rocking member and the driving member to shift the latter to accomplish said alternate engagement.

HERMAN G. PAPE.
